UNITED STATES PATENT OFFICE.

WILLIAM E. ELLIOTT, OF GRAND RAPIDS, MICHIGAN.

FASTENER-GUIDE FOR BUTTON-SETTING TOOLS.

1,032,390.

Specification of Letters Patent.

Patented July 16, 1912.

Application filed January 10, 1912. Serial No. 670,371.

To all whom it may concern:

Be it known that I, WILLIAM E. ELLIOTT, a citizen of the United States of America, residing at Grand Rapids, in the county of Kent and State of Michigan, have invented certain new and useful Improvements in Fastener-Guides for Button-Setting Tools; and I do hereby declare the following to be a full, clear, and exact description of the invention, such as will enable others skilled in the art to which it appertains to make and use the same.

My invention relates to improvements in fastener guides for button setting tools and more particularly to hand tools for the purpose, and its object is to provide such tools with a guide that will properly adjust and hold the fastener whereby the same will be driven through the fabric in proper position, and it consists essentially of a guiding member recessed to receive the fastener and adapted to move to a position to engage the prongs of the fastener and hold the same in proper alignment and substantially at right angles to the surface of the fabric through which they are to be driven as will more fully appear by reference to the accompanying drawings, in which:

Figure 1 is a side elevation of a hand tool 30 for setting fasteners of the wire staple style with my device applied thereto; Fig. 2 a front elevation of the jaws of the same in the position shown in Fig. 1; Fig. 3 a side elevation with the jaws partially closed; Fig. 4 a front elevation of the same in position as in Fig. 3; Fig. 5 a plan view of the device as in Fig. 1; Fig. 6 an inverted plan of the upper jaw with the guide attached thereto showing a longitudinal section on the line 6-6 of Fig. 1; Fig. 7 a detail of the pivot of the guide showing a vertical section on the line 7-7 of Fig. 3; Fig. 8 an enlarged perspective of a button, and a fastener of the type shown in the preceding figures; Fig. 9 is a side elevation of a modified device for setting the three pronged or so-called "Heaton" fastener; Fig. 10 a plan view of the device; Fig. 11 an inverted plan of the upper jaw of the same with my modified guide attached showing a horizontal section on the line 11-11 of Fig. 9; Fig. 12 a front elevation of the jaws in position as in Fig. 9; Fig. 13 the same partially closed; Fig. 55 14 a side elevation of the same in position as in Fig. 13; Fig. 15 an enlarged sectional

detail of the pivot for the guide; and Fig. 16 a perspective detail of one of the fasteners.

Like numbers refer to like parts in all of the figures.

1 represents the upper jaw and 2 the lower jaw of a hand tool for setting button fasteners of the staple form.

3 represents a spring mounted on the upper jaw.

7 is an arm fixed on the lower jaw 2 and having an offset end to engage the spring. When the jaws are fully opened the offset end of this arm engages the spring 3 and depresses it into contact with the upper side of the jaw 1.

4 is a pivoted guide below the upper jaw and preferably in the form of a plate of sheet metal pivoted to the upper jaw intermediate the ends and in contact with the undersurface of said jaw when the jaws are fully opened where it is held by a shoulder 8 on the arm 7 engaging the inner end thereof and overcoming a spring 6 which

spring tends to move the guide out of contact with the said jaw. Thus when the jaws are fully opened, the upper jaw, the spring 3 and the plate 4 are all in close relation and each is recessed in the end to simultaneously receive the eye of a button. As soon, however, as the jaws are partially closed the guide 4 is moved away from the jaw 1 by the spring and down upon the fastener which latter enters lateral recesses 90 in the jaw and is guided and held thereby in proper position for entering the fabric. The guide is stopped in this position by a shoulder 9 on the upper jaw engaging with the inner end of the guide. When the jaws are fully closed and the fastener clenched the guide is again moved up against the upper jaw out of the way by contact with the fabric in which the fastener is inserted.

By this device any swinging out of the proper adjustment on the part of the fastener is prevented and accurate work insured.

In the modified form shown in Figs. 9 to 15 inclusive the upper jaw 1^a of the tool, the spring 3^a, and the guide 4^a are modified to adapt the device to the form of fastener shown in Fig. 16, being recessed at one side to receive the eye and fastener and the recess in the guide 4^a is enlarged to suitably embrace the three prongs of the fastener and thus prevent the same from swinging

out of proper adjustment. Otherwise the device is the same as that shown in Figs. 1 to 8 inclusive.

From the foregoing description the operation of the device is obvious without further explanation.

What I claim is:—

1. In combination with a button setting tool having opposing jaws one of which is 10 adapted to receive the eye of a button, a pivoted guide normally close to said jaw when the jaws are opened, and adapted to receive the eye of the button and also adapted to move away from said jaw to engage 15 and guide a fastener whenever said jaws are moved toward each other.

2. In combination with a button setting tool having opposing jaws, one of which is adapted to carry a button and fastener, a 20 guide pivoted to said jaw and having a slot to receive the eye of the button, said slot also being laterally enlarged to receive the fastener, and means for automatically moving said guide toward and away from said jaw as the jaws of the tool are opened or closed.

3. A button setting tool, comprising jaws pivoted to each other, the upper jaw being

slotted to receive the eye of a button with a fastener suspended therein, a guide pivoted 30 to said jaw intermediate its ends and having its outer end slotted to receive said eye, said slot being laterally enlarged to receive the fastener, a spring to move the guide away from the jaw, a member on the other 35 jaw to engage the guide and move it toward said jaw, and means for limiting the movement of the guide away from the jaw carrying the button and fastener.

4. A button setting tool, comprising two 40 jaws pivoted to each other, a spring above the upper jaw normally spaced apart therefrom, a movable guide below the said jaw, said spring, jaw and guide each having a slot to receive the eye of a button and the 45 guide slot laterally enlarged to receive a fastener, and an arm fixed on the lower jaw adapted to engage the spring and guide and move the same close to the upper jaw when the jaws are opened. 50

In testimony whereof I affix my signature in presence of two witnesses.

WILLIAM E. ELLIOTT.

Witnesses:

PALMER A. JONES,
L. V. MOULTON.
